[21] Appl. No.: **953,396**

The ornamental design for a box blank, substantially as shown and described.

[22] Filed: **Oct. 23, 1978**

DESCRIPTION

[51] Int. Cl. .... **D9—03**

FIG. 1 is a top plan view of a box blank embodying our new design, the bottom plan view being substantially the same in appearance; and FIG. 2 is a side elevational view of the blank shown in FIG. 1.

[52] U.S. Cl. **D9/432**

The box blank is constructed of material of conventional thickness, and the dashed lines in the drawing represent fold lines.
